UNITED STATES PATENT OFFICE.

DAVID H. PAYNE AND JEROME H. PAYNE, OF TROY, NEW YORK.

CLOTHES-LINE PULLEY.

SPECIFICATION forming part of Letters Patent No. 223,947, dated January 27, 1880.

Application filed November 1, 1879.

To all whom it may concern:

Be it known that we, DAVID H. PAYNE and JEROME H. PAYNE, of Troy, in the county of Rensselaer and State of New York, have invented a new and Improved Clothes-Line Pulley, of which the following is a specification.

Figure 1 is an elevation of the pulley, partly in section. Fig. 2 is a plan of the same, partly in section.

Similar letters of reference indicate corresponding parts.

The object of this invention is to provide a horizontally-revolving pulley for suspending clothes-lines, and one around which the line with clothes hanging upon it can be easily pulled without injury to the clothes.

The invention consists of a horizontal disk from the edges of which several curved arms project outward and downward and several corresponding straight arms project outward and upward, with a ring or rim fixed over and upon the points of each set of arms.

In the drawings, A represents the disk; B, the lower curved arms; C C, the upward-projecting arms, and D D the rings or rims set upon the points or tips of the arms B C. The disk A has a hole, a, bored vertically through its center, and it is suspended in position by a bent rod, E, (shown in dotted lines, Fig. 1,) which passes through the hole a, being held thereon by the nut b.

By the upward, downward, and outward projection of the arms B C, a groove, F, is formed about the center of the pulley, and in this groove F the line rests.

The curves of the lower arms, B B, tend to keep the line from slipping down from the pulley; but should the line, because of its slackness or because of the weight of clothes upon it, tend to slip downward, it (the line) will be checked and held up by the lower ring or rim, D, that projects beyond the arms B B at their interspaces.

We are aware that clothes-line pulleys with projecting curved arms have been used; but they are objectionable, because the clothes so readily become torn upon the uncovered tips of the arms.

This pulley may be made in two parts and united at the center, or be made in a single casting. In the present instance it is made in two parts or sections that are united at their bases, as shown, by screws, rivets, or other convenient device.

Having thus described our invention, we claim as new and desire to secure by Letters Patent—

The combination of the disk A, having central hole, a, the downwardly-curved arms B, 60 and the upwardly-projecting arms C, each series of arms having a ring, D, on their tips, as described, to form a suspension clothes-line pulley.

DAVID HENRY PAYNE.
JEROME HAMILTON PAYNE.
